RAZOR BLADE HOLDER

Elbert A. Robertson, 2230 Rosecrans, Gardena, Calif., and Jerry L. Ogle, 10242 Virginia, South Gate, Calif.

Filed July 10, 1964, Ser. No. 381,674

1 Claim. (Cl. 30—32)

This invention relates to surgical instruments, and more particularly to a razor or the like.

Although the present invention will have a great many applications other than those disclosed herein and should not therefore be limited thereto, the invention has been found to be especially useful as a hair outliner. That is, barbers have found it useful as a device for trimming hair around the ears and on the neck.

In the past, prior art straight razors, as distinguished from safety razors, have been expensive to manufacture and to assemble. In order to obviate stropping, a straight razor with a replaceable blade has been employed. However, such a razor has likewise been expensive to manufacture, and therefore has been difficult to operate. Prior art razors have also been relatively weak in their mechanical construction.

In accordance with the present invention, the above-described and other disadvantages of the prior art are overcome by providing a razor blade holder including a body having a longitudinal slit therein extending completely through one end thereof. The body thereby has a pair of fingers on each side of the slit. Means are also provided which are actuatable to hold said fingers tightly against a razor blade in the slit, and thereby to restrain movement of the razor blade in it.

In accordance with a feature of the present invention, the body of the razor blade holder may be made of a flexible or resilient plastic material so that the fingers may be pushed apart or pulled together. The razor blade holder of the present invention is therefore inexpensive to manufacture.

In accordance with another feature of the invention, the ends of the fingers are provided with means to snap together to hold the fingers in pressure contact with a razor blade. This means may be molded integrally with the razor blade holder body. This makes the assembly of a removable razor blade between the body fingers an easy matter.

In accordance with another feature of the present invention, projections are provided in between the fingers to fit in holes through the razor blade. This keeps the razor blade in a secure position between the fingers and in a position fixed relative thereto.

Still another feature of the present invention incorporates a one-piece U-shaped guard for a razor blade in the holder. This construction is less expensive to manufacture and stronger than razor blade guards of the prior art.

The above-described and other advantages of the present invention will be better understood from the following description when considered in connection with the accompanying drawings.

In the drawings which are to be regarded as merely illustrative:

FIG. 1 is a side elevational view of a closed straight razor constructed in accordance with the present invention;

FIG. 2 is a view similar to FIG. 1 with a razor blade guard shown in its open position;

FIG. 3 is a broken longitudinal sectional view taken on the line 3—3 of the razor shown in FIG. 1;

FIG. 4 is a broken longitudinal sectional view taken on the line 4—4 of the razor shown in FIG. 1;

FIG. 5 is a transverse sectional view through a razor

2

blade and a razor blade holder taken on the line 5—5 in FIG. 2;

FIG. 6 is an end elevational view of the holder shown in FIG. 2; and

FIG. 7 is a longitudinal sectional view of the holder similar to the view of FIG. 3 with a pair of holder fingers spaced apart and without a razor blade therebetween.

In FIG. 1, a razor 10 is shown including a plastic guard 11 having a U-shaped construction as shown in FIG. 3, and a razor blade holder or body 12 which has much the same shape as the metal portion of a conventional straight razor. Body 12 is slit at its right end as shown in FIG. 7.

Razor blade holder 12 is likewise made of a flexible or resilient plastic material and is provided with a flange at 13 on a finger 14 which extends around a projection 15 on a finger 16 as shown in FIG. 7.

Holder 12 is pivoted about a pin 17 that extends through the ends of legs 18 and 19 of guard 11, as shown in FIG. 4.

Also as shown in FIG. 4, holder 12 is provided with shoulders at 20 and 21 which keep holder 12 spaced from the interior surfaces of guard legs 19 and 18 respectively.

Holder 12, except for a bore 22 therein as shown in FIG. 4 to accommodate pin 17, is solid to a point indicated by a dotted line 23 in FIG. 2. At this point, as indicated in FIG. 7, fingers 14 and 16 begin to separate. A razor blade is indicated at 24 in FIG. 2 and is in fact held tightly between fingers 14 and 16 as shown in both FIGS. 2 and 3. Finger 16 is provided with a recess at 25 to accommodate blade 24. Finger 14 is provided with a similar recess 26.

The plastic of guard 11 and holder 12 may be nylon, if desired, to facilitate a snap fit of flange 13 over projection 15. Razor blade 24 may be entirely conventional.

This blade may have a size as shown in the drawings, which may be to scale. The razor blade 24 so illustrated is in fact a conventional blade which is presently commercially sold on the open market. Blade 24 therefore has holes at 27 and 28 through which projections 29 and 30 project respectively, projections 29 and 30 being projections from finger 14 as shown in FIG. 7. A third projection 31 that extends along the upper edge of blade 24 also extends, integral with finger 14 as shown in FIGS. 2, 5 and 7, away therefrom. Projection 31 serves to keep blade 24 straight within body 12.

As shown in FIG. 7, flange 13 has a beveled surface at 32 and a notch 33 having a beveled surface 34.

Similarly, projection 15 has a beveled surface 35 to engage surface 32 frictionally and slide thereunder. Projection 15 also has a beveled surface at 36 to fit in pressure contact with and to mate with surface 34 in flange notch 33.

From the foregoing, it will be appreciated that holder 12 may be made easily and economically due to the fact that it may be injection molded or otherwise molded of nylon. The flexibility or resilience make it possible to mold holder 12 with fingers 14 and 16 all in one piece. The snap fit of projection 15 in notch 33 of flange 13 makes it possible to assemble and disassemble blade 24 between fingers 14 and 16.

Projections 27, 28 and 31 with recesses 24 and 26 maintain blade 24 in a strong and secure fixed position between fingers 14 and 16 as shown in FIGS. 2 and 3.

The use of U-shaped guard 11 as shown in FIG. 3 also provides a strong yet economical construction.

Although only one specific embodiment of the invention has been described and illustrated, many changes and modifications thereof will, of course, suggest themselves to those skilled in the art. The invention is therefore not to be limited to the specific embodiment selected for this disclosure, the true scope of the invention being defined only in the appended claim.

What is claimed is:

A razor blade holder comprising: a body having a longitudinal slit therein extending completely through one end thereof; said body thereby having a pair of fingers on each side of said slit, said body being made of a flexible material to permit movement of said fingers toward and away from each other; and a projection on one of said fingers, the other of said fingers having a notch therein to receive said projection, said fingers being movable toward each other until said projection falls in said notch and said fingers are thereby held tightly against a razor blade in said slit to restrain any movement of the razor blade therein, said projection being fixed to the end of said one finger to extend longitudinally therefrom, said other finger having a flange extending from the end thereof toward said one finger, said flange having said notch therein to ride over said projection, an edge of said notch being located in a position to slide frictionally over said projection only upon springing of said fingers by an application of pressure thereon to force said fingers together, the snap fit thus produced thereby keeping said fingers in pressure contact with a blade to hold the same securely in a fixed position relative to said fingers, said flange having a beveled surface at the edge thereof to ride up on said projection, said notch having a beveled surface to
